DESIGN FOR A MATCH-SAFE.

The Schedule referred to in these Letters Patent and making part of the same.

TO ALL WHOM IT MAY CONCERN:

Be it known that I, F. W. This invention relates to a design for a hanging receptacle for matches, formed from cast metal, in imitation of carved wood, the receptacle itself representing a wicker-basket, surrounded by a vine, which forms a base, and a means of support for the match-safe, all as fully shown in the accompanying illustration.
